Joe W. Coffman and Frederick O. Trump, Binghamton, N. Y., assignors to General Aniline & Film Corporation, New York, N. Y., a corporation of Delaware

Application November 6, 1947, Serial No. 142,360

Term of patent 14 years

(Cl. D64—11)

To all whom it may concern:

Be it known that we, Joe W. Coffman and Frederick O. Trump, citizens of the United States, residing at Binghamton, in the county of Broome and State of New York, have invented a new, original, and ornamental Design for Combined Printing and Developing Machine, of which the following is a specification, reference being had to the accompanying drawings, forming a part thereof.

Fig. 1 is a perspective view of a combined printing and developing machine showing our new design.

Fig. 2 is a front view of the machine of Fig. 1.

Fig. 3 is an end view; and

Fig. 4 is a plan view, respectively, of the said machine.

We claim:

The ornamental design for a combined printing and developing machine, substantially as shown.

JOE W. COFFMAN.
FREDERICK O. TRUMP.
